UNITED STATES PATENT OFFICE.

AUGUST F. HILLEKE, OF BIRMINGHAM, ALABAMA.

APPARATUS FOR CONCENTRATING ORES.

Application filed April 26, 1920. Serial No. 376,835.

To all whom it may concern:

Be it known that I, AUGUST F. HILLEKE, a citizen of the United States of America, residing at Birmingham, in the county of 5 Jefferson and State of Alabama, have invented certain new and useful Improvements in Apparatus for Concentrating Ores, of which the following is a specification.

My invention relates to an apparatus for 10 concentrating ores and like materials.

My invention is more particularly concerned with an apparatus of a comparatively simple and inexpensive character which is especially suited for the separation 15 of the fine particles of iron oxide in crushed iron ore (which is typical of the fines to be recovered from any crushed stock) from the larger particles of silica and other foreign matters of lower specific gravity than the 20 iron, to the end that the loss of iron in the tailings may be reduced and that a product may be obtained, which by nodulizing and cintering will, from an economic point, compete effectively with much higher grade ores 25 than that under treatment.

I have practiced my invention in the concentration of the low grade red hematite ores of Alabama, which in many cases are too high in silica, alumina and other foreign 30 matter to be commercially used. Experiments on a commercial scale by magnetic separation and by the use of a Wilfley table have been only partially successful, in both cases the loss of iron in the tailings being 35 too high to develop an effective economic use of the product in competition with higher grade ores.

My invention deals with another phase of the problem of effectively utilizing low grade 40 ores which are of such character and so placed as to be capable of being mined by the use of steam shovels, as when the latter method of mining is available the entire seams can be taken and the cost of mining 45 the seams materially reduced. Such a practice however involves a material increase in the silicates to be eliminated in the concentrating process. The object of my invention is to devise an apparatus which will effectively 50 and cheaply eliminate the greater percentage of foreign matter in the crushed stock and will itself produce a substantial percentage of fines and a large percentage of partially refined product which is in most 55 suitable shape for effective and economic

separation on a Wilfley table or other equivalent separator.

The chief problem encountered is that involved in the separation in a water or liquid bath of the small heavier particles of iron 60 ore from the larger but lighter particles of silica and other foreign matter, and I utilize the principle of suspending the finer particles in a separating, washing and concentrating tank by the control and direction of 65 the currents in the bath to the end that a substantial percentage of the fines are discharged in concentrated form ready for use and that the fine iron ore tending to pass off with the coarser foreign matter is washed 70 from the latter and delivered in part to the tank or other separating means and in part as a semi-concentrated product to the Wilfley table or other separator where the separating process is finished, or where the semi-refined product may be again collected and 75 returned in circuit through the combined separator, washer and concentrator.

In the practice of my invention for separating ore, the stock to be treated is first 80 crushed to sufficient fineness, preferably by preliminary crushing to size it and by finishing the product in a ball mill, it being necessary to reduce the product to the necessary fineness to make possible the separation of 85 silica, alumina, their compounds and other constituents from the iron in sufficient quantity to make a concentrate of the desired character. The next step is to deliver the crushed ore to a screen showered with 90 water, thereby causing the smaller particles to pass through the screen and the larger particles to pass over the screen, and as these larger particles contain only small particles of iron, they are delivered direct to the ref- 95 use or tailings pile. The elimination of these coarser particles increases the percentage of iron content in the finer particles which pass through the screen and this partially refined product is delivered by a 100 trough in contact with water to the combined separator, washer and concentrator which forms the most important and essential element in my invention. Here three operations are accomplished, as follows:

The semi-concentrate is discharged into the upper end of a tank supplied with water or other fluid in such manner as to produce a rising current which gradually increases in volume from the upper intake end 110

to the lower discharge end of the tank. This rising current of water will wash all of the very fine particles of ore from the coarser particles of ore and foreign matter as the 5 latter descend towards the bottom of the tank and this upward flow of water is just sufficient to carry off all of these very fine particles through a suitable overflow port and thence to a settling basin where the 10 fines concentrates settle out and is ready to be nodulized and sintered. This concentrator contains somewhat more than fifty per cent iron and extracts approximately fifty per cent of the total iron from the original 15 ore. This recovery represents one of the operations.

The second operation takes place in connection with the discharge of the coarser particles of ore and foreign matter and consists in conveying this material from the concentrating tank and as an agitated mass against a reverse flow of water as the preferred means to effectively wash off from the larger particles of matter the finer ore 25 particles still adhering thereto. This second washing of the larger particles is the second and perhaps the most important step of my invention as upon it depends the economic practicability of the process.

30 As a third and final step, the finer particles, thus washed from the larger particles passing off to the refuse or tailings pile, are returned in part to the tank where they may pass off with the larger particles of 35 ore to a final concentrator which may be a Wilfley table or any other standard concentrating or separating apparatus which will effectively treat the semi-concentrated product so as to collect therefrom an additional percentage of fines containing more 40 than fifty per cent iron, as well as middlings which are too high in iron to be discarded and these middlings may be returned through the ball mill or direct with the 45 stock into the separating tank for retreatment. The concentrates from the table and the fines recovered from the combined separator, washer and concentrator are mixed and constitute the concentrated product of 50 my apparatus which, when cintered or nodulized, becomes a high grade available product.

As illustrative of an apparatus suitable for carrying my invention into effect, reference is made to the accompanying drawings, in which:—

Fig. 1 illustrates a plant for the crushing, grinding, screening and separating of ores.

Fig. 2 is a side view partly broken away 60 of the combined separator, washer and concentrator.

Fig. 3 is a reverse side view of Fig. 2 also partly broken away to illustrate the baffle.

Similar reference numerals refer to similar 65 parts throughout the drawings.

According to my invention, as illustrated, the low grade ores as mined by a steam shovel or in any other manner are preliminarily crushed until reduced to sufficient fineness, say to a two inch and finer size. This 70 product is charged into the bin 1 and delivered therefrom for further reduction, into a ball grinding mill 2 from which the finely reduced product is delivered to a screen 3 where it is showered with water from a 75 spray 4, the smaller particles being caused to pass through the screen and out through a chute 5 and the larger particles to pass over the screen and be carried by an elevator 6 to the refuse or tailings pile. The iron content in that portion of the crushed material which has passed through the screen and through trough 5 is delivered thereby, in contact with water, to the combined separator, washer and concentrator, which is 80 shown in detail in Figs 2 and 3. This comprises an elongated V-shaped tank 7 with its bottom sloping from the end adjacent to the chute 5 to the other or discharge end 8 of the tank which is provided with a series of 85 vertical overflow apertures 9 at different levels, all being disposed so as to discharge into a chute 10 for carrying off the fines. The tank, on the side adjacent to the trough 5, is provided with an adjustable baffle plate 95 11, this plate extending from and co-extensively with the top edge of one side of the tank towards the opposite side wall of the tank near the bottom thereof and fitting closely between the end walls of the tank. 100 The lower edge of this baffle is left free and is controlled in its adjustment with relation to said opposite side by the provision of a series of set screws 12 which extend through threaded openings in the tank and have their 105 heads engaged in seats 13 near the lower edge of the adjacent face of the baffle. These screws can be adjusted so as to set the lower edge of the baffle at the desired spacing from the opposite tank side, which spacing may 110 and in practice is caused to vary gradually from the upper to the lower end of the tank. In practice this free edge of the baffle is set at approximately one-eighth of an inch from the opposite side of the tank at its lower 115 edge, which clearance is reduced until it disappears at the upper end of the baffle. Water is supplied to the tank behind and below the baffle and must rise with an up current increasing from nothing at the intake end for the screenings to the maximum current flow at the outlet discharge end 8. One supply of water is delivered through a pipe 14 into a water box 15 on the outside of the tank behind the baffle, this box having 120 a feed opening 16 at its bottom end opposite the upper end of the baffle. The bottom of the tank instead of terminating in a V is interrupted and joined to a screw conveyor tube 17 having at its lower 125 130

end a water inlet pipe 18 and having near its upper end another water inlet pipe 19 and beyond that a discharge 20 from the conveyor. The conveyor tube, which thus forms the bottom for the tank, is provided with a series of inlet openings 21 closely spaced along its top surface and through these openings the coarser particles, working downwardly past the baffle 11, gain access to the conveyor tube and are there engaged by a screw conveyor 22 which runs the full length of the tube and delivers these coarser particles to the discharge 20, the conveyor being driven by a gear 23 meshing with a similar gear 24 driven by the motor 25. It is to be noted that the water entering through the feed water line 19 flows counter to the feed in the coarser material by the screw conveyor which both agitates the particles and causes them to rub against each other with an abrasive action. This agitation of the particles in the absence of the water stream is intended to facilitate the action of the water in detaching the finer particles of ore adhering to or tending to move off with the coarser particles and cause the same to pass back in suspension in the water through the inlet openings 21 into the tank and thence to pass up with the circulation of water and join the concentrates passing off through chute 10.

The feed water line 18 delivers a supply of water through the conveyor tube to the lower end of the tank, while the feed water line 14 delivers a water supply to the upper end of the tank, and the feed water line 19 delivers water to a greater or less degree throughout the length of the tank, and all these water supplies enter the tank below and behind the baffle plate 11 and must therefore gain access to the main body of water above the baffle by passing through the gradually enlarging clearance between the lower end of the baffle and the adjacent side wall of the tank. This produces an up-flow or current through the tank which can be finely adjusted to the condition and character of the ore and which is capable of holding in suspense in the body of liquid in the tank the finer, though heavier, particles of ore while permitting the coarser particles of ore and foreign matter, though the latter may be lighter, from working downwardly between the baffle and the tank and gaining access to the conveyor tube through the inlets 21. The fines discharged through the trough 10 are ready to be nodulized, cintered or otherwise treated and will be found to contain in excess of fifty per cent iron, notwithstanding the ore would grade as low as thirty per cent in iron.

The semi-refined or partly concentrated product passing off through the discharge 20 is delivered to a Wilfley table or equivalent separator 26 driven by a motor or equivalent prime mover 27 and having a dis-

charge trough 28 for the fines and a discharge trough 29 for the middlings, which latter can be conducted to an elevator 30 and returned thereby to the ball mill and thence again treated according to my process 70 already described. If desired these middlings may be short circuited to the table itself for retreatment thereon or to the tank 7 as may be desired.

It is a special object of the combined 75 separator, washer and concentrator 7, that it can be adjusted to control the agitation of the body of water or fluid therein so as to most efficiently separate the fine ore particles from the larger though lighter particles of 80 silica and foreign matter, this being accomplished by the greater tendency of the finer particles to be held in suspension in the water while the larger particles will tend to fall to the bottom, and these finer particles 85 in suspension pass off with the overflow water as fines.

It is most important to note that inevitably a substantial percentage of fine ore will tend to pass off with the silica and larger ore 90 particles as the latter are carried by the screw or other conveyor and my experience has been that these finer particles thus carried off are not very efficiently separated and recovered by the Wilfley table or equivalent 95 separator. I am able to obtain a greatly increased percentage of fines by the novel idea of washing these fines back by a counter flow of water or by moving the coarser particles under agitation through an agitated 100 body of water capable of bringing these finer particles into suspension therein and conveying them back to the separator tank or equivalent device, such as a settling basin, for their ultimate recovery. It is also to be 105 noted that I obtain an external adjustment for the baffle 11 which affords a very convenient means for regulating the water supply according to the results being obtained on the grade of material under treatment, thus enabling the apparatus to be 110 quickly brought to and maintained at its most efficient operating condition.

This invention is not intended to be restricted in scope to the specific embodiments 115 shown, but contemplates such modifications as come within the spirit and scope of the claims.

Having thus described my invention, what I claim as new and desire to secure by Letters Patent, is:—

1. In an apparatus for the separation and concentration of ore and the like, a tank having an adjustable baffle disposed lengthwise thereof and extending from one side 125 towards the opposite side of the tank, means to introduce water below the baffle, means to introduce the material to be treated above the baffle, and means to produce a variable clearance between the free edge of said baffle 130

and the said opposite wall of the tank to control the feed and effect a differential distribution of water to the separating portion of the tank.

5. 2. In an apparatus for the separation and concentration of ore and the like, an elongated, substantially V-shaped tank having a conveyor in its bottom and an overflow, a baffle extending from end to end of the tank 10 and inclined obliquely downwardly from one side and terminating adjacent to the bottom of the other side, means to regulate the clearance between the free bottom edge of the baffle and the tank, means to introduce feed water below the baffle, and means 15 to introduce the material to be separated above and near one end of the baffle and an overflow near the other end of the baffle.
3. In an apparatus for the separation and 20 concentration of ore and the like, an elongated substantially V-shaped tank having a conveyor in its bottom and an overflow for fines, a baffle extending obliquely downwardly from one side and terminating adjacent to the bottom of the other tank side, external means to regulate the clearance between the free bottom edge of the baffle and the tank, said baffle being shaped and relatively disposed to produce a differential 25 clearance between its free end and the tank to effect a variable upflow of water lengthwise of the tank, means to introduce feed water below the baffle, and means to introduce the material to be separated above the 30 baffle.

4. In an apparatus for the separation and concentration of ore and the like, a tank having an elongated substantially V-shape disposed at an incline with a material feed 40 chute at its upper end, there being a fine outlet port at its lower end, means to introduce water along the bottom of the tank, and means to admit the water from the bottom into the upper portion of the tank 45 through a continuous aperture gradually enlarging from the upper to the lower end of the tank.

5. In a separator, washer and concentrator, a V-shaped sloping tank having a 50 conveyor tube at its bottom with inlet apertures, adjustable regulating means to form and control the cross sectional area of a restricted passage connecting portions of the tank above and below said means, means to introduce water below the regulating means, means to introduce material above the regulating means, and means to feed water to the tank through the conveyor tube.

6. In a separator, washer and concentrator, a V-shaped sloping tank having a 60 fines overflow and a conveyor tube at its bottom with inlet apertures, a transverse sloping baffle adjustable at its bottom edge to regulate the passage connecting the portions of the tank above and below the baffle, 65 means to introduce water below the baffle, means to introduce material above the baffle, and means to feed water to the tank through the conveyor tube, said means comprising one water inlet at the lower end of the conveyor tube and a second water inlet near the upper or discharge end of the conveyor tube.

7. In an apparatus for the separation and concentration of ore and the like, an elongated tank having downwardly converging 75 side walls, an ore feed chute near one end of the tank, a longitudinal transverse baffle extending from one side wall to provide a water passage clearance between its free edge and the other side of the tank, means 80 to adjust said baffle to vary said clearance, the baffle and its adjusting means being adapted to produce a clearance which gradually enlarges from the feed chute towards the other end of the tank, an overflow of the 85 lighter particles at said latter end, means to feed water below the baffle to cause an upflow through said clearance, and means to collect and carry off the heavier particles settling through said water passage clearance.

8. In an apparatus for the separation and concentration of ore and the like, an elongated tank of varying depth and having downwardly converging side walls, a longitudinal transverse baffle extending from one side wall to provide a water passage 95 clearance between its free edge and the other side of the tank, means to adjust said baffle to vary said clearance, the baffle and 100 its adjusting means being adapted to produce a clearance which gradually enlarges from the shallower towards the deeper end of the tank, an overflow for the lighter particles at said latter end, means to feed water below 105 the baffle to cause an upflow through said clearance, means to feed the material to be separated above the baffle at the shallower end of the tank, and means to collect and carry off the heavier particles settling 110 through said water passage clearance.

In testimony whereof I affix my signature.

AUGUST F. HILLEKE.
